UNITED STATES PATENT OFFICE.

WILLIAM H. HANEY, OF CINCINNATI, OHIO, ASSIGNOR TO HENRY KORF,
JR., OF SAME PLACE.

AIR-DISTRIBUTER FOR CANDLE-MOLDS.

SPECIFICATION forming part of Letters Patent No. 268,888, dated December 12, 1882.

Application filed September 11, 1882. (No model.)

To all whom it may concern:

Be it known that I, WILLIAM H. HANEY, a citizen of the United States, residing at Cincinnati, in the county of Hamilton and State of Ohio, have invented certain new and useful Improvements in Air-Distributers for Candle-Molds, &c., of which the following is a specification.

My invention comprises a peculiarly-constructed air-distributer especially adapted for use in the contracted spaces between a series of candle-molds. The principal member of the distributer is a main pipe or trunk disposed longitudinally of the mold chest or box and near the top of the same, suitable perforations being made in the upper side of said main to receive short necks projecting from lateral or branch pipes, to which pipes secondary branches are attached by slip-joints. These primary and secondary branches or laterals are inserted between the molds, and are slotted or perforated at top, so as to insure an upward discharge of air, as hereinafter more fully described, and pointed out in the claim.

In the annexed drawings, Figure 1 is a longitudinal section through the upper part of a candle-mold provided with my air-distributer, the central portion of the apparatus being broken away. Fig. 2 is a sectioned plan of the same. Fig. 3 is a transverse section of a portion of the upper part of the mold, the center plate thereof being removed. Fig. 4 is an enlarged section, showing the various members of the air-distributer detached from each other.

A represents the box or chest of a candle-mold of any approved construction, the molds proper, B, being so applied to said chest as to locate their open upper ends within the troughs C C'. Of these vertical molds as many may be fitted in the chest as can be conveniently attended to.

Located between the troughs C C' is a detachable center plate, D, the removal of which affords access to the interior of chest A.

Arranged longitudinally of the chest, and under the center plate, D, is the main pipe or trunk E, supported at one end by a pipe, F, communicating with any suitable blower or other device capable of producing the desired air-blast. The opposite end of trunk E may

rest on a concave flange, G, or other proper support. Furthermore, the upper side of this trunk is pierced at H to admit short conical necks I, projecting downwardly from the primary laterals or branches J, as more clearly seen in Fig. 3. The ends of these branches near the necks I are open, while their opposite ends are closed, slots or perforations K being made in the upper surface of these branches to permit the discharge of air. Adapted to slip over the open ends of these branches are the secondary laterals J', having longitudinal slots K' and closed outer ends.

To apply this air-distributer to the ordinary candle-mold machine, the center plate, D, is removed, and the trunk E is then passed down into the chest A, and one end of said trunk is allowed to rest on flange G, or its equivalent support, while the opposite end of main E has the pipe F slid into it, said pipe F being adapted to fit tightly within the chest A. One of the primary branches J is then passed down into the chest, and the neck I is inserted in the proper hole, H, in the trunk E, which act disposes said branch horizontally and in close proximity to one set of molds of trough C, as seen in Fig. 3. The secondary branch, J', is then slipped onto the first section, J, thereby disposing said secondary branch near the molds of trough C'. These operations are repeated until all the primary and secondary laterals have been applied to the trunk E, and the plate D is then secured in its proper position. The stock is now poured into the troughs C C' and allowed to flow down the molds B, steam being admitted through a suitable pipe, L, into chest A, to keep said molds at a proper temperature. As soon, however, as it is desired to cool the molds the steam is shut off, and the blower is then started for the purpose of forcing air into chest A. The air is driven through pipe F into trunk E, and thence through necks I into the laterals J J', from whence the air escapes at the slots K K'. Now, as these slots or perforations are on the upper side of the branches J J', it is evident the air first comes in contact with the hot plates of troughs C C', and then descends and escapes at a ventage, as seen at N in Fig. 2. Consequently the stock in the molds is cooled in the most uniform man-

ner; and there is no loss from the candles being cracked or otherwise injured.

I claim as my invention—

In combination with a candle-mold of the 5 class described, an air-distributer consisting of the perforated trunk E H and primary slot-ted laterals J K, having necks I, fitting in the openings H of said trunk, the secondary slot-

ted laterals J' K' being slipped onto said primaries J K, in the manner described.

In testimony whereof I affix my signature in presence of two witnesses.

WILLIAM H. HANEY.
